AUTOMOBILE-BODY HEATER

Earl C. Booth, Columbus, Ind., assignor to Noblitt-
Sparks Industries, Inc., Columbus, Ind., a cor-
poration of Indiana

Application March 25 1940, Serial No. 325,673

6 Claims. (Cl. 98--2)

My invention relates to automobile-body heaters of the circulating fluid type and has for its object the provision of means facilitating the control of the heated air discharged from such heater. More specifically, it is my object to provide a heater having two air-outlets directed in different directions with means for successively opening or successively closing such outlets by the operation of a single control member which may be remote from the heater.

In carrying out my invention, I employ a heater which is preferably adapted for mounting upon the dash of the automobile in a central location and which has a pair of air-outlet openings disposed in opposite side walls. Associated with each of such outlets I provide a pivoted closure connected by a link to a rotating member mounted on a horizontal axis between the two outlet openings. The positions of the rotating member and of the points at which the links are connected thereto are so selected that when the rotating member is rotated to move one of the closures from closed to open position the position of the other closure will be substantially unchanged. To rotate the rotating member, and thereby control the respective positions of the shutters, I employ a remote control device, preferably in the form of a Bowden wire connected eccentrically to the rotating member.

30 The accompanying drawing illustrates my invention: Fig. 1 is a front elevation of an automobile-body heater equipped with my invention; Fig. 2 is a side elevation of the heater shown in Fig. 1 with portions of the heater-casing broken away; Fig. 3 is a section on the line 3—3 of Fig. 2; Fig. 4 is a fragmental view similar to Fig. 3, but showing the outlet closures in a different condition of adjustment; and Fig. 5 is a small-scale elevation illustrating the disposition 40 of the heater within the automobile body.

The heater shown in the drawing comprises a casing 10 containing a core 11 through which hot water from the engine cooling system circulates, a fan 12 for causing air-flow through such core, and an electric motor 13 for driving such fan. As shown, the casing 10 has a semi-circularly curved lower wall provided with two main outlet openings 14 and 15. The vertical side walls of the heater-casing are shown as provided 45 with auxiliary air-outlet openings 16 adapted for connection to conduits 17 extending to defroster nozzles 18 located adjacent the windshield 19 of the automobile, as will be clear from Fig. 5.

55 As shown, the heater-casing 10 has an air-inlet in its front wall, such inlet being covered with a suitable grille 21, the fan 12 is arranged in rear of the core to draw air therethrough, and the outlet openings 14, 15, and 16 are located 60 near the rear of the casing substantially in the

plane of the fan 12. While this specific arrangement is preferred, it is not essential.

The main air-outlet openings 14 and 15 are provided respectively with pivoted closures 25 and 26. As shown, the closures 25 and 26 are 5 pivotally mounted on pivots 27 in the casing 10 adjacent the upper ends of the openings with which they are respectively associated; and the closures are so shaped that, when closed, they conform to the shape of the casing. 10

For the purpose of operating the closures, there is pivotally mounted on the rear wall of the casing and between the openings 14 and 15 an operating member 30, conveniently in the form of a disk. A link 31 having one end connected to the closure 25 below the pivotal axis thereof and the other end connected to an eccentric point on the disk 30, serves to interconnect the closure 25 with the disk. A second link 32, having one end connected to the closure 26 below its pivotal axis and the other end connected to an eccentric point on the disk 30 connects the closure 26 to the disk. In the specific arrangement shown, the inner end of the link 31 is curved upwardly and connected to the disk 25 30 at a point substantially directly below the disk-axis when the closure 25 is closed; while the inner end of the link 32 is curved downwardly and connected to the disk 30 at a point spaced in a clockwise direction from the point 30 at which the link 31 is connected to the disk.

For the purpose of rotating the disk 30 to control the closures 25 and 26, I prefer to employ a Bowden wire 34 which, as shown, is connected to an eccentric point on the disk 30 and which 35 extends through the customary sheath 35 to a control member 36 desirably located on the instrument board 37 of the automobile. The end of the sheath 35 is anchored to the heater casing by a suitable clamp 38 disposed close to the 40 disk 30.

An important feature of my invention resides in the arrangement of the links 31 and 32 and of the points at which they are connected to the disk 30. In the particular arrangement illustrated, the disk 30 is arranged to be rotated through an angle of about 120° by the operation of the Bowden wire, and the points at which the two links are connected to the disk are spaced apart a distance of about 60° or approximately 45 half the angle through which the disk 30 is rotatable. With both closures 25 and 26 closed, as indicated in full lines in Fig. 3, the disk 30 is at the counterclockwise limit of its rotation, and the pivotal connection between the disk and the 50 link 31 is substantially directly below the disk-axis. If the Bowden wire is operated to produce a disk-rotation of about 60° in extent in a clockwise direction, the parts will assume the 55 respective positions illustrated in dotted lines in 60

Fig. 3. In that movement of the disk, the inner end of the link 31 will be carried sufficiently far to the left to swing the closure 25 to an open position; but the inner end of the link 32 will move in a generally vertical direction, with the result that the position of the closure 26 will have undergone no substantial change. In other words, during the stated movement of the disk 30, the inner end of the link 31 moves generally parallel to that link, while the inner end of the link 32 moves generally perpendicularly to that link. If the disk 30 is now rotated through an additional angle of about 60°, the inner end of the link 32 will be moved to the right, generally parallel to the link 31, to open the closure 26; but, since the inner end of the link 31 moves generally vertically, or generally perpendicularly to the link 31, the closure 25 will remain open. The position of the parts when the disk has reached the clockwise limit of its rotation is shown in Fig. 4, where both closures 25 and 26 are fully open. If the Bowden wire 34 is now operated in reverse direction to cause counter-clockwise rotation of the disk 30, the sequence of operations just described is reversed, the closure 26 being closed during the first half of disk-rotation and the closure 25 being closed during the second half of such rotation.

The inner ends of the links 31 and 32 are curved as illustrated to prevent them from coming into contact with each other as the disk is rotated and thereby to prevent their interfering with disk rotation. Movement of the Bowden wire in its sheath will ordinarily be accompanied by sufficient friction to hold the disk 30 in any desired position of adjustment.

As will be clear from Fig. 5, I contemplate that the heater will be mounted on the dash of the automobile in an approximately central location so that the outlet opening 14 will be directed toward the feet of the driver and the opening 15 toward the feet of a front-seat passenger. If the Bowden-wire control member 36 is in the normal position illustrated in Fig. 2, the disk 30 will be at the counterclockwise limit of its rotation and both closures 25 and 26 will be closed. Under these circumstances, all air discharged from the casing 10 will pass through the conduits 17 to the defroster nozzles. If the driver is alone in the car and desires that the car-body be heated, he will draw out the control member 36 half-way to rotate the disk 30 to the dotted-line position shown in Fig. 3, thus opening the closure 25 while leaving the closure 26 closed. Should there be a front-seat passenger, the driver will draw out the control member 36 to the limit of its movement, thus causing opening of both closures as illustrated in Fig. 4.

Since movement of the disk 30 from the full-line position to the dotted-line position of Fig. 3 will entail some, although slight, movement of the closure 26, first inwardly and then outwardly, I prefer to form that closure so that it can swing inwardly a slight distance from a position flush with the wall of the casing in order that it may be flush with such wall when the disk 30 is in its normal position.

It will be noted that in the drawing the axis of the disk 30 is spaced from the center-line of the casing. This disposition of the disk is not essential, and is employed merely to simplify manufacture by making it possible for the two links 31 and 32 to be the same.

I claim as my invention:

1. In an automobile-body heater having a cas-

ing provided with two air-outlet openings in opposite walls, pivotally mounted closures associated respectively with said openings and each movable between open and closed positions, a closure-operating member mounted between said outlet openings and rotatable from a normal position to an extreme position through a fraction of a revolution about its axis of pivotal mounting, and a link connecting each of said closures with an eccentric point on said closure-operating member, the point at which one of said links is connected to said closure-operating member being so disposed as to move generally parallel to the link during the first half of movement of said closure-operating member from normal to extreme position and generally perpendicular to the link during the last half of such movement of the operating member, and the point at which the other of said links is connected to said closure-operating member being so disposed that it moves generally perpendicular to such link during the first half of the stated movement of the closure-operating member and generally parallel to such link during the last half of such movement.

2. The invention set forth in claim 1 with the addition of a control device remote from said heater and operatively connected to said closure-operating member to move it selectively to its normal position, its extreme position, or an intermediate position.

3. The invention set forth in claim 1 with the addition of a Bowden wire connected at an eccentric point to said closure-operating member, extending to a point remote from the heater, and operative to move said closure-operating member selectively to its normal position, its extreme position, or an intermediate position.

4. In an automobile-body heater having a casing provided with two air-outlet openings in opposite walls, pivotally mounted closures associated respectively with said openings and each movable between open and closed positions, a closure-operating member mounted between said outlet openings and rotatable from a normal position to an extreme position through a fraction of a revolution about its axis of pivotal mounting, and a link connecting each of said closures with an eccentric point on said closure-operating member, the points at which such links are connected to said closure-operating member being so disposed that as each moves generally parallel to its associated link when the closure-operating member is swung about its axis the other will move generally perpendicular to its associated link.

5. In an automobile-body heater having a casing provided with two air-outlet openings in opposite walls, closures associated respectively with said openings and each movable between open and closed positions, closure-operating means disposed within said casing and operative to open and close said closures successively, and means including a manually operated control member disposed at a point remote from the heater for controlling said closure-operating means.

6. In an automobile-body heater having a casing provided with two air-outlet openings, closures associated respectively with said openings and each movable between open and closed positions, and means including a single control member remote from the heater and operatively connected to both said closures for successively opening them and successively closing them.
